UNITED STATES PATENT OFFICE.

MONROWE WALTER JONES, OF ARDMORE, INDIAN TERRITORY.

SAW-FILING MACHINE.

No. 845,359.

Specification of Letters Patent.

Patented Feb. 26, 1907.

Application filed June 14, 1906. Serial No. 321,759.

To all whom it may concern:

Be it known that I, MONROWE WALTER JONES, a citizen of the United States, residing at Ardmore, District No. 21, Indian Territory, have invented certain new and useful Improvements in Saw-Filing Machines; and I do hereby declare the following to be a full, clear, and exact description of the invention, such as will enable others skilled in the art 10 to which it appertains to make and use the same.

My invention relates to gin-saw filers, and is an improvement upon Patent No. 815,175, dated March 13, 1906, granted jointly to 15 myself and Joseph A. Dennis.

My object is to provide an adjusting mechanism whereby when the device is once adjusted all of the saws may be successively filed without resetting the same.

A further object is to provide means for yieldingly securing the file-operating mechanism whereby when a solid surface is encountered by the files the operating mechanism will yield and prevent breakage of the 25 files.

Other objects and advantages will be hereinafter made clearly apparent in the specification and pointed out in the claims.

In the accompanying drawings I have 30 shown the preferred form of my invention.

In said drawings, Figure 1 is a side elevation of my improved filing mechanism applied to use. Fig. 2 is a top plan view showing my improved adjusting mechanism. Fig. 3 is a detail elevation of a portion of the 35 file-operating mechanism, and Fig. 4 is a detail sectional view as seen from line 4-4, Fig. 3.

Referring to the figures by numerals of reference, 1 indicates the supporting-frame of my improved saw-filing mechanism, to which is secured a bifurcated tubular member 2, in which is mounted a longitudinally-movable shaft 3, said shaft having a head 4 at its 45 outer end to which are secured files 5, said files being of the usual form and preferably crossed to engage teeth upon a saw 6. The head 4 is also provided with suitable guide-arms 7, which are designed to engage the 50 blade of the saw and keep the files in alignment therewith.

The inner end of the shaft 3 is provided with a cross-arm 8, to which is secured, by

means of bolts 9, a plate 10, said plate being disposed at a distance from the cross-arm 8 and adapted to receive therebetween a cam 11, said cam being eccentrically mounted upon a shaft 12, carried by the frame 1. One side of the cam 11 is provided with a hub-section 13, which has a projection thereon forming a shoulder 14, with which is adapted to engage a projection 15 on a fly-wheel 16, said fly-wheel being rigidly secured to the shaft 12 by means of a set-screw or the like 17. The projections 14 and 15 are so constructed as to form segments of circles in cross-section, the circumference of said segments being less than one-half the circumference of the complete circle, so that when 20 said projections are disposed into the path of each other and in their normal positions a space will be left between the meeting ends thereof, the object of so constructing the projections being to add to the strength thereof and prevent casual breaking of the same. A pinion 18 is rigidly secured to the shaft 12 by means of a set-screw 19 and at the opposite end of the shaft from that upon which the fly-wheel is mounted and is adapted to mesh with a driving-gear 20, mounted upon a stub-shaft 21 in the supporting-frame 1, said shaft being extended through one side of the frame and has mounted thereon a crank 22, by which means rotation is applied to the shaft 12. The cam 11 is loosely mounted on the shaft 12 and is held normally rigid therewith by means of a coiled spring 23, said spring being secured at one end to the pinion 18 and at its opposite end to the cam 11, the object in so mounting said cam being that 25 when the files 5 encounter a bent or rusty tooth or other obstruction the rotation of the cam 11 will be checked, thereby imparting tension to the spring 23 and gradually checking the rotation of the shaft 12, so that by 30 the time the projection 15 on the fly-wheel 16 reaches the shoulder 14 on the hub 13 the momentum of the fly-wheel 16 will have been practically stopped and the impact of the projection 15 and shoulder 14 materially 35 reduced. As soon, however, as the files have been released from the obstruction the spring 23 will direct the cam 11 to its normal position on the shaft 12 and the filing operation continued. A spacing-ring 23^a is disposed between the hub 13 and the face of the 40

fly-wheel 16, thereby preventing lateral movement of the cam 11 on the shaft 12.

By this construction it will be readily seen that the liability of breaking the files is very

5 slight, owing to the fact that the cam 11 will yield, and thereby direct the files slowly over the obstruction and prevent any undue jar or strain upon the operator or the parts of the machine. In order to support the files 5 and 10 insure that they will properly engage the teeth of a saw 6, I have secured to the free end of the tubular member 2 a pair of supporting-arms 24, said arms being pivotally mounted on the opposite sides of said tubular member and adjustably secured to wings 15 25, carried by the tubular member 2, said wings having slots 26 therein, through which take a bolt 27, the free ends of said supporting-arms resting upon spacing-collars 28, said 20 collars being of the usual or well-known form. In order to adjust the files at a suitable distance from the periphery of the saw, I pivotally secured between the supporting-arms 24 a gage-arm 29, said arm being adapted 25 to engage the peripheries of the collars 28. A link 30 is pivoted at one end to the lower end of the gage-arm 29 and is provided at its opposite end with an elongated slot 31, through which take the bolts 27 and by 30 which means the gage-arm is held in its adjusted position.

In placing my improved filing device in position upon a gin-saw the supporting-arms 24 are first rested upon the collars 28 upon 35 each side of one of the saws, after which the files 5 are disposed in position upon the teeth, and when the proper stroke of the shaft 3 has been ascertained the gage-arm 29 is disposed against the periphery of one of the 40 collars 28 and secured in its adjusted position by means of bolt 27. After the several parts

have been thus adjusted they may be placed in coöperation with each succeeding tooth without changing the adjustment of the same.

45

What I claim is—

1. A device of the class described comprising the combination with a saw-filing machine; of supporting-arms pivotally secured to a portion of said machine and having their outer ends arranged to rest on the saw-mandrel, means to adjustably secure said supporting-arms to the machine, a gage-arm pivotally secured to said supporting-arms and arranged to bear against the mandrel, a link 50 pivoted to said gage-arm and having its opposite end adjustably secured to the clamping means of one of said arms. 55

2. A device of the class described comprising the combination with a saw-filing machine; of a pair of supporting-arms pivotally secured at one end to said machine and having their opposite ends directed above and in engagement with a mandrel of a saw, an angular gage-arm pivotally secured to said 60 supports and adjacent their outer ends, one portion of said gage-arm being adapted to engage and bear against the mandrel, a link pivoted to the lower end of said gage-arm and having a slot at its opposite end, means 65 engaging one of said supports and the slot in said link to adjustably secure the support and link to the machine and similar means for adjustably securing the opposite support to the machine. 70

In testimony whereof I have signed my name to this specification in the presence of two subscribing witnesses.

MONROWE WALTER JONES.
